METHOD FOR SIZING CORN

Oliver W. Steele, St. Louis, Mo., and Lester J. Pfister, El Paso, Ill.

Application April 3, 1939, Serial No. 265,656

1 Claim. (CL 209—235)

The invention relates to new and useful improvements in sizing and separating methods and mechanism, and more particularly to such improvements in vibratory mechanisms for minutely and successively separating corn into a large number of accurately and closely dimensioned sizes.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combination and improvements herein shown and described.

The accompanying drawings, referred to herein and constituting a part hereof, illustrate one embodiment of the invention, and together with the description, serve to explain the principles of the invention.

Of the drawings:

Fig. 1 is a side elevation of a mechanism embodying the invention;

Fig. 2 is a vertical longitudinal section through Fig. 1;

Fig. 3 is a transverse vertical section taken on the line 3—3 of Fig. 1;

Fig. 4 is a perspective of a screen and screen frame;

Fig. 5 is a perspective of the means for returning the undersize from one screen to the head of the next, and of the discharge means for the oversize;

Fig. 6 is an enlarged diagrammatic showing of screen elements; and

Fig. 7 is a vertical section, partly diagrammatic, of a different assembly of the screen elements and illustrating the steps of a method of size separation.

The invention is directed to provide a method and mechanism capacitated especially for sizing seed corn into a relatively large number of closely dimensioned sizes preparatory to use in mechanical planters. It is customary in large planting operations to employ mechanical corn planters, which will operate reliably only with closely sized seed corn so as to insure that the proper number of grains, no more and no less, are planted. The problem of pre-sizing the seed corn is both difficult and important. To insure accurate dropping of the grains by the mechanical planter, without skipping or overplanting, the grains must be accurately pre-sized as to thick-

ness, length and breadth of the kernels. The sizing is very close, and for the better and more expensive kinds of seed, such as hybrid seed corn, the seed must be graded very closely, and desirably within $\frac{1}{64}$ inch limits in both width and thickness. Under these requirements, from six to thirteen, or more, different sizes of kernels may be found on the same ear of corn, and a corresponding number of sizing operations must be performed to separate these sizes. Not only is uniform planting required in order that there may be no skipped hills or over-planted hills, but the cost of hybrid seed corn is many times that of open pollinated varieties and accurate planting is necessary to prevent waste of seed.

Objects of the invention are to provide method and mechanism for accurately sizing the kernels as to both width and thickness within the close limits indicated and to provide simple, strong and inexpensive mechanism for effecting such sizing; to provide for effecting a complete sizing through the entire dimensional size ranges of the corn in one mechanism and by one continuous method and operation; to provide for sequential screenings, certain of the screenings sizing the corn for width and other of the screenings sizing it for thickness; that is, after the kernels have been classified to a plurality of predetermined close dimensions as to thickness, the kernels of each of these classes are then further classified to a plurality of predetermined close dimensions as to width, thus providing a double dimensional close sizing for all the kernels; to provide for subjecting the corn to successive screenings on groups of screens, the one group having screen openings of different shape from those of another group, the screens in each group having screen openings of the same shape but of different dimensions; more particularly to treat the kernels on a group of screens having oblong openings of gradually lesser width in successive screens, and then treating the separate size classifications thus derived on a group of screens having circular openings of gradually lesser diameter in successive screens, thereby to obtain the required double-dimensional commercial sizes; to provide a mechanism of relatively large capacity and efficiency, especially as to the areas of screens employed, which is portable and simple to operate, and to assemble and disassemble; which is economical of power consumption, and automatically maintains the screens clear without use of unblinding means. To this end, all of the seed corn is run over the first or largest size screen, preferably entirely from the head to the

tail thereof, while undergoing the screening operation, the oversize kernels being discharged from the tail end of the screen, the screen being relatively long and narrow. The screens are vibrated vertically or transversely, whereby the kernels are given a dancing or bounding movement as contrasted with a sliding or longitudinal movement, and the kernels when striking the screen are moving transversely thereto and are largely presented endwise to the holes, thus greatly increasing the screening efficiency for a given area, and also shortening the time necessary for complete size separations. The undersize kernels passing through a screen are conveyed to the next smaller screen and delivered, preferably, near the head end of that screen, and subjected again to a similar sizing operation, and this is continued through the entire range of sizes. One group of screens has screen openings of one shape, and another group has screen openings of another shape, the sizes of like shaped screen openings in a group being graduated in size to effect the desired classification, as by sixty-fourths of an inch, for the width or for the thickness of the kernels. Means are also provided for taking off the doubly-dimensioned commercial sizes from the various screens at the points of completion of such sizing.

The method comprises treating the corn by successive screenings to separately and minutely size or classify it according to one dimension, for instance, thickness, and then treating each of those separate thickness classifications by successive screenings to separately and minutely size each separate thickness classification according to another dimension, for instance, width; that is, by successive screenings for thickness, the corn is separated into a plurality of very close and relatively minute sizes, which gives the necessary close classification as to thickness; these close and minute thickness sizes are then separately successively screened to effect a correspondingly very close and relatively minute sizing again as to width; the combined repeated close screenings for both dimensions giving the desired close and minute classification as to both thickness and width. This is carried out in practice by passing the corn over a succession of screens wherein the screen openings are relatively long and narrow, preferably oval in shape, the openings in a lower screen being smaller than in that just above, the sizes varying usually in the width only of the opening, to give the classification for thickness of kernels. The groups thus separately closely and minutely classified for thickness are then passed over a succession of screens wherein the openings are substantially uni-dimensional, that is circular, the openings in a lower screen being smaller than those in the screen next above, to effect classification for widths of kernels in the corn already classified for thickness of kernels, the classification thus being carried to any degree of closeness and minuteness as to both width and thickness of the kernels. The planting machine thus is supplied with kernels of the same size within, say, sixty-fourths of an inch in both dimensions. It will be understood that the foregoing general description and the following detail description as well, are exemplary and explanatory of the invention, but are not restrictive thereof.

Referring now in detail to the embodiment of the invention illustrated by way of example in

the accompanying drawings, in Figs. 1 to 6 the structural features and vibrating means for a battery of screens are disclosed without reference to the method, or the structural features which are especially employed in practicing the method. These latter are best shown in Fig. 7. In Figs. 1 to 6, a rigid supporting frame is provided, which may be conveniently made of structural angle bars, and is shown having at either side a plurality of vertically-disposed members 1, 2 and 3 on one side, 4, 5, and 6 on the other, and these are fixed to and extend upwardly from floor rails 9 and 10, and are connected together by horizontally-disposed bars 7 and 8 near the bottom part thereof and by cross-frame braces 11 and 12, having their ends at either side of the frame fixed to the vertical members 1 and 4 and 3 and 6. At their top ends the two sets of vertical members are connected together by horizontally-disposed angle bar 13 at one side and 14 at the other, the flat, horizontal top pieces of these angles serving to support the vibratable screen mechanism. The embodied means for positioning the screens either horizontally or at a longitudinal inclination comprises screw threaded rods 16, threaded into one end of the floor rails 9 and 10. These level adjusting screw rods have hand wheels 17 and locking nuts 18.

A plurality of screen members or frames are disposed in superposed relation with intervening means for returning the undersize from a screen above to the head of the screen next below, and these screen members or frames are mechanically connected or clamped together to constitute for operating purpose an integral structure. They are resiliently mounted on the supporting frame so as to be vertically vibrated as a unitary device, capacitated to repeatedly and successively separate out seed corn quickly and with precision within the required close size dimensions. As embodied, assembly screening units are provided having a two-part nestable frame, one part of the frame, that is, one of the detachable frames, carrying the screen and the other part or frame carrying the plate which returns the undersize toward the head of the next screen.

As embodied, a frame 21, preferably rectangular, comprises side plates 22 and 23, a head plate 24 and a plurality of bottom cross braces 25, the foraminous screen plate 26 being mounted within the frame and supported on the cross braces 25. There is no wall at the tail end of the screen, the oversize flowing off over the tail end of the screen. As embodied, the frame 22 is supported in nested relation upon a frame 31, comprising side plates 32 and 33, a head end plate 34 and a tail end plate 35 extending across within and a short distance from the tail end of the side plates 32 and 33. A backwardly and downwardly inclined return plate 36 is mounted within the frame 31, its high end being at the cross wall 35, the plate being inclined downwardly toward the head end and terminating some desired distance short of the plate 34. The undersize of the screen 26 next above falls upon plate 36 and is supported and directed by the plate toward the head end of the next screen beneath. The length of the plate 36 will be such that the undersize will be delivered sufficiently near to the head of the screen below to insure efficient separation. When the screen frame and return plate frame are assembled, the side plates 22 and 23 of the screen frame rest on the side plates 32 and 33

of the return frame, the head plate 24 of the screen frame rests on the head plate 34 of the return frame, and the tail ends of the side plates 22 and 23 abut against the vertical edges 37 and 38 of the vertically-extending plates 39 and 40 of the return plate frame, the end of the screen 26 being just above the cross frame plate 35. An end wall 43 connects across between the end plates 38 and 39 of the return plate frame, and between the tail end plate 35 and this wall 43 is an inclined plate 44 having its high end against the plate 40 and its low end at the bottom of the discharge opening 45 formed in the bottom part of end plate 38. The oversize corn flows from the screen 26 onto the inclined plate 44 and is discharged from the unit through opening 45.

The number of these two-part units to be employed will depend upon the required degree of dimensional minuteness of separation of the corn, as to thickness, breadth and length, and to meet commercial requirements with hybrid seed corn, from six to thirteen units will ordinarily be used together. These are superimposed and clamped together and are vibrated as a mechanical unit. The embodied form of means for uniting or fixing the desired number of the units together comprises a plurality of cross beams 51, 52, 53, 54 through which pass vertically-extending rods 56, 57, 58 and 59, the beams being supported on nuts 55 screw threaded on the rods, said rods at their upper ends pass through a rectangular top frame 60. The composite frame units 22, 32 are set one upon another, the bottom frame resting on the cross bars 51-54, and the top frame 60 resting on the top of the uppermost screen unit frame 22. Nuts 61 are screw threaded on the top ends of the rods 56-59, and are turned down to clamp the entire structure to form a solid vibrational unit.

The resilient mounting for the assembled screening units, as embodied, comprises a plurality of compression coil springs 69, 70, 71, 72 and 73, having their bottom ends nested in cups 74, 75, 76, 77 and 78, fixed to the top faces of the respective horizontal frame members 13 and 14. At either side of the supporting frame, a plurality of flat springs 81, 82 each have one end 83, 84 fastened to the top supporting frame members 13 and 14, and have their opposite ends 85, 86 fastened to the under face of the top plate 60 of the vibratable unit. These also act as resilient supports for the vibratable screening units and further serve to keep the suspended screen units in aligned position without interfering with the free vibrational movement.

Means are provided for supplying the unsized corn to the head end of the top screen, and, as shown, said means comprises a hopper 91, having a bottom opening 92 above the head end of the uppermost screen 26, and having an inclined adjustable valve plate 93, which is slidably supported on a bracket 94 and held in adjusted position by a clamp screw 95 to regulate the flow of the unsized corn into the separator. Flexible connections 97 are connected to the openings 45 to carry away the oversize corn from the respective screens. The oversize from the lowermost screen flows into the receiving hopper 98 and out at the orifice 99. The undersize from the lowermost screen goes into the receiving hoppers 100 and 101 and out through the orifices 102 and 103.

Any suitable form of vibrating mechanism may be employed, and as shown herein a vibrator 109 of the type known commercially as the "Ajax-

Shaler shaker," which comprises two oppositely rotating unbalanced rotors is mounted on a cross support 110, carried on the top frame 60 of the vibratable screen unit. The shaker is driven from a motor 111, mounted on a cross support 112, by means of a belt 113. The support 112 is supported from the stationary supporting frame, being riveted to the horizontal top frame members 13 and 14 at either side.

In Fig. 7 is illustrated one commercial embodiment of the method and mechanism for classifying the corn both as to thickness and width to dimensions within sixty-fourths of an inch. By way of example, a highly efficient commercial arrangement of groups of screens with openings of two shapes in different groups and various sizes of each shape in the respective groups are shown in Fig. 7, the form of the openings being indicated at the left of the screens in said figure. Screens T¹ and T² have oval openings, respectively, $1\frac{1}{16}$ " x $\frac{3}{4}$ " and $1\frac{3}{16}$ " x $\frac{3}{4}$ ", and effect the first classification for thickness. (It will be understood that the dimensions employed are merely exemplary of one form of commercial practice.) The oversize from the screen T¹ is taken off as reserve, and not generally used for planting. The oversize from screen T², which has now been classified for thickness, is directed for further classification as to width of kernels, as indicated by routing line r¹ on to round hole screen W⁷ having openings of $2\frac{1}{16}$ ", and the undersize of that screen goes to screen W⁸ with openings of $2\frac{1}{16}$ " and the undersize from that to screen W⁹ with openings of $1\frac{1}{16}$ ". The oversize of each of these screens is taken off as doubly-dimensioned commercial sizes. The undersize from screen T² is directed for width classification to a round hole screen W¹ having openings of $2\frac{1}{16}$ " and the undersize from that screen goes to a screen W² having round openings of $2\frac{1}{16}$ ", these two screens sizing successively for width. The oversize from these screens are taken off as doubly-dimensioned commercial sizes as indicated by cs in Fig. 7. The oversize from screen T³ is directed as indicated by routing line r², for further sizing as to width together with the oversize from the screen T². The oversize from screen T⁴ is directed to a battery of screens W³ to W⁶ for width sizing of the kernels. These screens having, respectively, round screen openings of $1\frac{1}{16}$ " for the first to $1\frac{1}{16}$ " for the last, and the oversize from each of these screens is taken off as doubly-dimensioned commercial sizes, as indicated as cs. Certain small sizes are taken off as culls at various points, as indicated by c. As here arranged, an undersize from the first double classification as to thickness and width is reclassified again both as to thickness and width, primarily as to thickness and then as to width. In routing the kernels after one classification, as to thickness, for the second classification, as to width, they are selectively routed so as to minimize the bulk of the undersize handled on various screens. It will be understood that the classifications as to width and thickness relate to the two dimensions of the kernels other than their length, and the sequence may be varied so far as concerns the main features of the invention. The size of screen openings, the particular sequence of screens, both as to shape and size of openings, as exemplified in this particular commercial form, are exemplary of present preferred practice in applying the principles of the invention and are well adapted to closely size to

meet present practical planting conditions with planters now in use.

The invention consists in the novel steps, sequences, elements and combinations as pointed out in the accompanying claim, and it will be understood that departures may be made from the specific forms shown and described without departing from the principles of the invention and without sacrificing its chief advantages.

What we claim is:

The method of sizing corn into a plurality of closely dimensioned sizes which comprises successively screening the corn and by the separate successive screenings closely dimensionally classifying the kernels as to thickness, subjecting the 15

corn so classified as to thickness to further sequential screenings to classify it as to width and taking off the oversize from the various screens of the last-mentioned series of screenings as doubly-dimensioned commercial sizes, said successive screening steps each comprising passing the kernels of corn substantially horizontally while subjecting said kernels to rapid vertical vibration projecting them upwardly from the horizontal path and causing them to fall vertically on end, thereby to effect accurate screening as to width and thickness and to prevent clogging of the screens.

OLIVER W. STEELE.
